United States Patent Office

Des. 177,613
Patented May 8, 1956

177,613

COMBINED HAIR CURLER AND COMB

Joseph Lloyd Chiariello, Los Angeles, and Sidney Cox,
Inglewood, Calif.

Application August 31, 1955, Serial No. 37,734

Term of patent 7 years

(Cl. D86—8)

The figure is a perspective view of a combined hair curler and comb, showing our new design. The side opposite that shown is substantially similar thereto.

We claim:

The ornamental design for a combined hair curler and comb, as shown and described.
